UNITED STATES PATENT OFFICE.

JOSEPH M. DENNING, OF CEDAR RAPIDS, IOWA, ASSIGNOR TO PYRAMID POST AND POLE COMPANY, OF CEDAR RAPIDS, IOWA, A CORPORATION OF SOUTH DAKOTA.

MOLD FOR MAKING CEMENT FENCE-POSTS.

No. 909,875.

Specification of Letters Patent.

Patented Jan. 19, 1909.

Application filed October 20, 1908. Serial No. 458,621.

To all whom it may concern:

Be it known that I, JOSEPH M. DENNING, a citizen of the United States, residing at Cedar Rapids, in the county of Linn and State of Iowa, have invented certain new and useful Improvements in Molds for Making Cement Fence-Posts, of which the following is a specification.

The molds of the present invention is intended more particularly for the making of fence posts of the style shown in Patent No. 836,128, issued November 20, 1906, although the mold can be used for the making of fence posts of a shape other than that disclosed in such patent.

The present invention relates to metal molds for the making of cement fence posts or similar elongated structures; and the object of the invention is to provide a mold, the parts of which are easily separable for the purpose of removing the post after it has set and hardened, thereby enabling the post to be quickly and easily removed and the mold to be cleaned, if necessary, prior to subsequent usage. In the making of cement structures of this kind, it sometimes happens that pieces of cement or mortar adhere to the mold after a post has been drawn therefrom, so that, unless provision is made for the cleaning out of such fragments, the posts thereafter molded will have rough spots or imperfections in the surface. The mold of the present invention is so constructed that it can be easily collapsed by a suitably applied shock or jar, which frees the molded post from the mold and at the same time permits the two sections to be cleaned prior to again assembling them for future operations.

The invention consists in the features of construction and combination of parts hereinafter described and claimed.

In the drawings, Figure 1 is a side elevation of the mold with the molded post ready for discharge; Fig. 2 a similar view showing the mold partly disassembled for the purpose of removing the completed post; and Fig. 3 a cross sectional view, showing the interlocking members.

The mold of the present invention is particularly shaped to form a fence post of trefoil design in cross section, although, obviously, the configuration of the mold could be varied considerably without changing the character of the invention.

The mold consists of a section 4, which may be termed the body section, and a section 5, which may be termed the cover section and, as shown in Fig. 3, the edges of the cover section overlap the edges of the body section sufficiently to hold the sections clamped together and provide a joint which will prevent the escape of cement when poured into the mold. The sections are slightly tapered, from end to end, which gives to the mold, as a whole, a tapered formation; and, in order to prevent the outflow of cement from the smaller end, during the molding operation, a cap 6 is provided which is secured to a bracket 7, which latter is riveted or otherwise rigidly attached to the cover section of the mold, the opposite or enlarged end of the mold being left open to receive the cement. The cover section, at its enlarged end, is provided with an outwardly projecting foot 8 which, as shown, is composed of a bar or section of T iron, riveted or otherwise secured to the cover section of the mold. The tapered formation of the body and cover sections is such that when the two sections are properly in register they will wedge together, which wedging action is possible by reason of the overlapping edges of the cover, which are carried around sufficiently to engage the sides of the body section and prevent disengagement of the two sections, save only by an endwise movement in the right direction. The sections are thus held together during the molding operation by the provision of a plurality of pins 9 which are entered diagonally through the cover and the side walls of the body section and diverge from one another from front to rear. The pins are preferably arranged in staggered relation to one another, so that when the cement is poured into the mold, holes, in staggered arrangement and extending diagonally through the post, will be provided for the reception of fastening means for holding the fence in place when applied.

When it is desired to use the mold, it is placed in a vertical position with the open end up, and the two sections wedged together and held by the insertion of the pins. The cement is then poured in in a fluid condition and thereafter allowed to set and harden. When in condition for removal, the mold is turned with its large open end

down, as shown in Fig. 1, and the pins removed by pulling them out from the holes, after which the foot of the mold is subjected to a shock or jar, preferably by striking it against the floor, which shock or jar serves to arrest the endwise movement of the cover section, allowing the body section, meanwhile wedged by the inclosed post, to be carried on down by its own momentum, thereby affording the necessary endwise movement to disengage the two sections previously wedged together. This action either entirely disengages the sections, allowing the mold to collapse and the post to be removed, or it sufficiently loosens the sections so that they can afterwards be taken apart without any difficulty. The arrangement is one which affords access to the interior of the body and cover sections, which can thus be easily cleaned if particles of cement or other substances are found to be adhering to the interior. Thereafter the parts can be readily assembled and the pins inserted for further molding operation.

25 What I regard as new and desire to secure by Letters Patent is:

1. A mold of the class described, comprising two sections formed to interlock together, and a foot on one of the sections adapted to im- 30 part a shock or jar to said section for the purpose of disengaging the sections, substan- tially as described.

2. A mold of the class described, comprising two sections of tapering formation adapted 35 to interlock together by means of a wedging action, and a foot on one of the sections adapted to impart a shock or jar to said section, for the purpose of disengaging the sections, substantially as described.

40 3. A mold of the class described, comprising two sections of tapering formation adapted to interlock together by means of a wedging action, a foot on one of the sections adapted to impart a shock or jar to said section for 45 the purpose of disengaging the sections, and pins entered through the sections for holding them in interlocked position to form holes in the completed post, substantially as described.

4. A mold of the class described, comprising 50 two interlocking sections, the edges of one of the sections overlying the edges of the other section, and a foot on one of the sections adapted to impart thereto a longitudinal movement for disengaging the sections, sub- 55 stantially as described.

5. A mold of the class described, comprising two tapering coöperating sections adapted to be interlocked by a wedging action, the edges

of one of the sections overlying the edges of the other section, and a foot on one of the 60 sections adapted to impart a shock or jar to said section for the purpose of disengaging the sections, substantially as described.

6. A mold of the class described, comprising two tapering coöperating sections adapted to 65 be interlocked by a wedging action, the edges of one of the sections overlying the edges of the other section, a foot on one of the sections adapted to impart a shock or jar to said section, for the purpose of disengaging the 70 sections, and pins entered through the sections for holding them in interlocked relation and in position to form holes in the completed post, substantially as described.

7. A mold of substantially triangular for- 75 mation, comprising a body section forming two sides of the mold, and a cover section forming one side of the mold the edges of said cover section overlying and engaging the edges of the body section, and a foot on one 80 of the sections adapted to impart a shock or jar to said section, for the purpose of disengaging the section by a longitudinal movement, substantially as described.

8. A mold substantially triangular in cross 85 section and tapering from end to end and composed of a body section forming two sides of the mold and a cover section forming the third side of the mold, the edge of said cover section overlapping the edges of the body section and interlocked therewith, and a foot on the cover section adapted to impart a shock or jar thereto, for permitting the sections to be disengaged by a continued move- 90 ment of the body section, substantially as 95 described.

9. A mold substantially triangular in cross section and tapering from end to end and composed of a body section forming two sides of the mold and a cover section forming the 100 third side of the mold, the edge of said cover section overlapping the edges of the body section and interlocked therewith, a foot on the cover section adapted to impart a shock or jar thereto, for permitting the sections to 105 be disengaged by a continued movement of the body section, and diagonally extending pins entered through the cover and the sides of the body section for holding the sections in interlocked position and positioned to form 110 holes in the completed post, substantially as described.

JOSEPH M. DENNING.
